UNITED STATES PATENT OFFICE.

CHARLES H. MILLER AND CARL H. MILLER, OF CLEVELAND, OHIO.

COMBINED GAS-BURNER AND GRATE-BAR.

1,108,207.

Specification of Letters Patent. Patented Aug. 25, 1914.

Application filed January 8, 1914. Serial No. 811,032.

To all whom it may concern:

Be it known that we, CHARLES H. MILLER and CARL H. MILLER, citizens of the United States, residing at Cleveland, in the county 5 of Cuyahoga and State of Ohio, have invented certain new and useful Improvements in Combined Gas-Burners and Grate-Bars, of which the following is a specification.

10 This invention relates to a combined gas burner and grate-bar as shown in the accompanying drawings in which—

Figure 1 is a plan view of the said bar or burner with the gas jets uppermost. Fig. 15 2 is a side elevation of the said bar partially sectioned at one end to show interior construction. Fig. 3 is a plan view of the bar the reverse of Fig. 1 or with the grate side uppermost. Fig. 4 is a cross section of the 20 bar.

The bar or burner *b* as thus shown is designed to be used for either gas or solid fuel according to the fuel available or that may be preferred, and can be easily changed 25 from one use to the other by a mere reversal or inversion of the bar. Thus, in Fig. 1, the said bar is shown as having its gas jets *g* exposed on top and adapted to burn a gaseous fuel, but this position is wholly reversed in Fig. 3 where the grid side or grids *c* are on top and the bar is in position to burn a solid fuel, like wood and coal. To these ends the said bars or burners *b* are tubular or hollow and preferably square or rectangular in cross section and are open particularly at their intake or front ends where a mixer can be attached or applied for gas, or they can be left open to supply air when solid fuel is used. In the latter case the air to 35 support combustion will be entrained through the interior of the tube and discharged at the jets *g* at the bottom of the bar in a more or less superheated state, thus

greatly facilitating combustion. The jets *g* are therefore employed whichever kind of fuel is consumed and in case of solid fuel the said bars possess the novelty of being hollow and supply heated air to combustion through a series of small orifices distributed uniformly the entire length of the bar. Several of the said bars are arranged side by side as usual when placed in a stove or furnace, and any approved means may be provided for rotating them individually or collectively to shake them down when used for 45 solid fuel or to invert them when burning gas. The grids or ribs *c* on said bar for supporting the solid fuel extend laterally at each side and may be varied in height above the surface of the bar, and of course 50 are down and out of the way when gas is used. The shape of the bar also is somewhat peculiar in this that it is nearly or quite 55 square in cross section and has a flat side with three jets *g* in a row transversely and 60 on the same plane and of the same length and affording a wide and uniform diffusion of the gas and heat.

What we claim is:

A combined gas burner and grate bar 70 substantially square in cross section and hollow interior and provided with burner jets in series transversely on one side and a series of transversely disposed grids on the opposite side adapted for burning solid fuel, 75 the said bar having an opening at one end and closed at the other and provided with trunnions at its ends on which it is reversible.

In testimony whereof we affix our signatures in presence of two witnesses.

CHARLES H. MILLER.
CARL H. MILLER.
